UNITED STATES PATENT OFFICE

ELMER BROBERG, OF ROCKFORD, ILLINOIS, ASSIGNOR TO ELCO TOOL & SCREW CORPORATION, OF ROCKFORD, ILLINOIS, A CORPORATION OF ILLINOIS

SHOE LAST

Application filed May 18, 1931. Serial No. 538,056.

The invention relates generally to shoe lasts and more particularly to shoe lasts having means for fastening heel parts thereto.

It is common practice in the manufacture of shoes to fasten heels to the last by means of a conventional wood screw, but because of wear incident to repeated use, the screw becomes dull and wears until it is no longer fit for service.

10 It is accordingly an object of the present invention to provide a last having improved heel fastening means permitting of the quick and easy replacement of the screw.

More specifically stated, it is an object of 15 the invention to provide a heel fastening means comprising a screw retaining bushing removably secured in the last by means operable from an external part of the last to release said bushing and thereby permit 20 renewal of the screw.

Other objects and advantages will become apparent in the following description and from the accompanying drawing, in which:

Figure 1 is a sectional elevational view 25 of a shoe last embodying a preferred form of the invention.

Fig. 2 is an elevational sectional view looking at right angles to the view shown in Fig. 1.

30 Fig. 3 is a view generally similar to Fig. 1 but showing the connecting means in retracted position.

Referring more particularly to the drawing, the invention in its preferred form is 35 embodied in a shoe last comprising a body section 10 to which a heel 11 is secured by the improved connecting means generally indicated at 12. The body of the last is customarily provided with a metallic bottom plate 40 13 rigidly secured in position by means such as screws 14.

The heel fastening means is carried in an 45 elongated vertical bore formed in the body of the last and having a reduced upper end 15. The fastening screw, designated 16, which serves to detachably connect the heel to the body is guided for longitudinal movement by means of a bushing 17 which is adapted to be received in the lower enlarged 50 end 18 of the bore. A shoulder 19 formed

by the relatively greater diameter of the bore section 18 serves to provide an abutting stop against which the upper end of the bushing engages. With its upper end in contact with the before-mentioned shoulder, the lower 55 end of the bushing is disposed substantially flush with the lower edge of the bottom plate 13. The head 20 of the screw 16 is slidably received in a central section 21 of the bore, the diameter of which is intermediate that of 60 the upper end 15 and the enlarged lower end 18.

Means is provided to normally move the screw 16 to retracted position as indicated in Fig. 3, and in the present embodiment of 65 the invention such means comprises a coiled spring 22 surrounding the screw and acting between the underside of its head 20 and a shoulder 23 formed in an axial counter bore 24 in the upper end of the bushing 17. Upward movement of the connecting screw 16 under the influence of the spring 22 is limited by a shoulder 25 formed at the upper end of the central bore section 21. When the connecting screw is retracted so that its 70 head abuts the shoulder 25, its lower end is substantially in the plane of the lower surface of the plate 13 as shown in Fig. 3, thus permitting of the removal of the last from the shoe.

80 The bushing 17 and its associated connecting screw 16 are removably secured in the bore section 18 by manipulative means operable from a point outside the last and without removing the face plate 13. To this end, 85 one or, if desired, two diametrically opposed arcuate notches 26 are formed adjacent the upper end of the bushing, the respective axes of the notches extending substantially transversely of the axis of the bushing. A 90 pair of spaced parallel holes 27 formed in the body section of the last and extending transversely of and tangentially intersecting the bore section 18 are adapted to receive similar members 28 preferably in the form of 95 screws which cooperate with the notches 26 of the bushing 17 to rigidly retain the latter against rotation and longitudinal displacement relative to the body 10 of the last.

100 The screws 28 are adjustably positioned

in their respective bores by threaded engagement with similar bushings 29 fitted in counterbores 30 of the bores 27. When the screws 28 are in assembled relation with the last, their headed ends 31 are received in shallow counterbores 32, and are readily accessible for removal or adjustment from the external surface of the assembled last.

It will be apparent that the bushing and its associated fastening screw may be inserted in the lower end of the bore with its notches 26 registering with the transverse holes 27, after which the screws 28 may be threaded into place to rigidly and non-rotatably position the bushing relative to the body of the last. The screw 16 will normally be retained in upper or retracted position as is indicated in Fig. 3 under the influence of the spring 22. In attaching a heel to the last, the parts are alined as indicated in Fig. 3 after which a tool may be inserted through the upper end 15 of the vertical bore to drive the screw to the position indicated in Figs. 1 and 2.

The bushing may be readily removed and the screw 16 quickly replaced by first removing the screws 28 which can be accomplished either in the assembled or disassembled condition of the last.

I claim as my invention:

1. A shoe last comprising, in combination, a body to which a heel is adapted to be detachably connected, means to detachably connect said body to the heel including a bushing with a transverse notch in its periphery, said body having a bore adapted to receive said bushing, a headed screw, the body of which is slidably received in said bushing with its head slidably positioned in said bore, a spring tending to move said screw to a retracted position, said body having a second bore extending transversely of and intersecting said first mentioned bore, and a screw entered in said second bore and movable into engagement with the notch in the bushing to lock the bushing against longitudinal movement relative to said body.

2. A shoe last comprising, in combination, a body to which a heel is adapted to be detachably connected, and heel-fastening means including a bushing, said body having an upright bore adapted to receive said bushing, a screw slidable in said bushing, and manually operable means mounted in said body and accessible from the outside thereof to engage said bushing tangentially and retain the latter in a longitudinally immovable position relative to said section.

3. A shoe last comprising, in combination, a body to which a heel is to be detachably connected and having a plate member rigid therewith, and heel-fastening means including a bushing, said body having a bore adapted to receive said bushing, said body plate having a hole in registration with said bore,

a screw slidably received in said bore, and manipulative means operable from the outside of said body when said heel is connected thereto to lock said bushing against displacement relative to said body.

In testimony whereof, I have hereunto affixed my signature.

ELMER BROBERG.
